UNITED STATES PATENT OFFICE.

CHARLES J. DUNBAR, OF KALAMAZOO, MICHIGAN.

LOOSE-LEAF BINDER.

Specification of Letters Patent. Patented June 27, 1916.

1,188,634.

Application filed April 28, 1915. Serial No. 24,385.

To all whom it may concern:

Be it known that I, CHARLES J. DUNBAR, a citizen of the United States of America, and resident of Kalamazoo, county of Kalamazoo, State of Michigan, have invented 5 certain new and useful Improvements in Loose-Leaf Binders, of which the following is a specification.

This invention relates to improvements in 10 loose leaf binders for filing systems and has for an object to produce a loose leaf binder which will positively secure the sheets of the system against accidental displacement.

A further object is to produce a loose leaf 15 binder which will readily permit of the removal and filing of sheets at any place in the system without having to remove and replace any of the sheets of the system each time access to certain sheets or the filing of 20 new sheets is desired.

These and other objects are attained in the binder described in the following specification and illustrated in the accompanying drawings in which;

25 Figure 1 is a perspective view of a binder embodying my invention. Fig. 2 is a sectional view taken on the line 2—2 of Fig. 1. Fig. 3 is a sectional view taken on the line 3—3 of Fig. 2. Fig. 4 is a side elevation looking in the direction of the arrow in Fig. 1. Fig. 5 is a fragmental perspective view of the end of a sheet mounting bar embodying a detail of my invention. Fig. 6 is a perspective view of a bar locking 30 sleeve embodying a detail of my invention. Fig. 7 is a perspective view of a part of a sheet adapted to be mounted in my improved binder.

The binder embodying my invention consists of two relatively movable side members 40 8 and 9 forming a frame and carrying sleeves 10 located in apertures formed therein, and a series of sheet mounting bars 11 removably located in the sleeves. These bars and their mounting sleeves constitute the 45 principal feature of my invention. The bars consist of two telescoping portions 12 and 13, each one of which is provided at one of its ends with a pin 14 adapted to engage a bayonet slot 15 formed in one of the sleeves. 50 The sleeves mounted in the apertures formed in the members 8 and 9, are secured therein preferably by soldering them in position, and are so positioned that the entrances of 55 the bayonet slots formed therein are located

to the outside of the binder. This is for the purpose of permitting each portion of the sheet mounting bars to be passed through its mounting sleeve to register with its co-operating portion extending from the opposite binder member. The outer portion 12 of the telescoping bars is made in the form of a tube adapted to receive the inner portion 13 and is larger in diameter than the portion 13 and for this reason requires a 60 larger sleeve to receive it than does the portion 13. The slots 15 are constructed in the manner shown in Figs. 3 and 6, so that after the pin 14 has been passed through the branch 16 of the slot, the portion of the 65 bar located in the sleeve may be rotated to pass the pin through the branch 17 of the slot, to lock the portion against accidental displacement from its mounting sleeve. To facilitate the locking, unlocking and re- 70 removal of the portions of the bars from the slots of their mounting sleeves I have provided squared apertures 18 in the portions 13, and squared apertures 19 in the closed outer ends of the tube portions 12, in which 75 a suitable wrench or key is adapted to be inserted to unlock the portions of the bar in order to remove them.

To adapt the binder to hold the desired 80 number of sheets, I have provided means for permitting relative motion of the side members 8 and 9 toward or away from one another, and of securing these members in their adjusted positions. This means as illustrated in the drawings, consists of a screw 85 threaded bolt 20 secured in the side member 8 and adapted to extend through a slot 21 formed in the side member 9. Mounted on this bolt is a thumb nut 22 to prevent relative movement of the members 8 and 9 after 90 the members have been brought to the desired position with relation to the sheets mounted between them. This means of securing relative movement and adjustment of the members 8 and 9 with relation to one 95 another does not constitute a detail of my invention however, since any suitable means may be provided for securing this relative movement of the members and of securing the members in their adjusted positions. 100

Binders embodying my invention may 105 contain any desired number of my improved mounting bars, and as illustrated in the drawings, may be adapted to mount sheets having apertures, slots, or as shown in the 110

sheet in Fig. 7, sheets having a combination of apertures 23 and slots 24. In certain commercial machines, such as adding machines of a certain type now on the market, the 5 sheets employed are provided with a series of slots located at intervals along one of their edges. Heretofore, these record sheets have been mounted in binders which contain transversely extending pins adapted to 10 occupy the slots of the sheets, and the binders were so constructed that they would clamp the sheets together to prevent accidental removal therefrom. The convenience of such a system is manifest since it was 15 but necessary to merely lift the desired sheets from the binder, make the desired entry thereon, and replace the sheet over its locking pins. This could easily be done with any sheet of the system since it was not 20 necessary to remove any of the sheets other than the desired sheet. However, the objection to such a system of filing has been that too strenuous a usage of the binder would result in the sheets bulging between 25 the adjustable members so that they would easily become loosened and fall out of the binder, with a possible loss and disarrangement of the record sheets. This has resulted in laws being enacted to prevent the use for 30 certain purposes, of loose leaf filing systems of this type. To use a filing system in which the sheets were provided with a series of apertures to be mounted upon a series of stationary pins, would also be disadvantageous 35 since to have access to any desired sheet or to permit of the ready filing of new sheets at any desired place in the system, would necessitate removing a certain number of sheets from the pins to the place where removal or 40 addition was to be made. This system although having its advantages, in that it complied with the requirements of the law, would also have its disadvantages in that it would be awkward and necessitate time consuming operations to keep the system in 45 proper condition. It is to overcome the inherent disadvantages of both of these systems that I have devised the binder herein described.

50 As illustrated in Fig. 7 my improved binder is adapted to be used with systems employing slotted sheets, by merely providing apertures 23 between the slots 24 of the sheets so that the removable sheet mounting 55 bar of my improved binder may pass through the apertures between the slots to lock the sheets positively in the binder, thus preventing accidental displacement therefrom. Access to and removal of any desired 60 sheet from the binder is permitted without having to disturb any of the other sheets of the system, by simply removing the bar occupying the apertures of the sheets. When the binder is in use during the time that removal and filing of sheets therein is being

done, both portions 12 and 13 of the bar passing through the apertures 23 of the sheets are removed from the binder so that each sheet may be slipped readily into its proper position or removed therefrom by 70 passing the slots 24 of the sheet over the bars adapted to engage the slots. When however, the binder is to be filed away, the sheet, mounting bar or bars are passed through the registering apertures 23 of the 75 sheets, and the portions of the bars are then locked in position by bringing the pins 14 into the portions 17 of the bayonet slots of the bar mounting sleeves, as above described. The relatively movable members of 80 the binder are then brought toward one another to properly clamp the sheets together and the tightening means for securing the members in their clamped position are then operated to secure the members together. 85 When the binder is to be again used the tightening means are loosened and the bars are removed by unlocking them from the slots of their mounting sleeves and removing both portions thereof so as to leave the 90 sheets in the binder free to be moved or replaced as desired.

Having thus described my invention, what I claim is:

1. A loose leaf binder comprising a frame, 95 a sheet mounting bar having its ends removably mounted in the sides of the frame and adapted to be removed through a side of the frame from the outer face thereof, one of said ends being incased within a sleeve secured in one side of the frame, said sleeve and end having coöperating locking means adapted to prevent displacement of the bar.

2. In a loose leaf binder the combination of a frame, a slotted sleeve mounted in the frame, a sheet-mounting bar removably mounted in the sleeve, and a pin mounted in the bar and adapted to coöperate with the slot in the sleeve to lock the bar in the frame.

3. In combination in a loose leaf binder, a frame having relatively adjustable members, a telescoping sheet-mounting bar removably mounted in and adapted to be withdrawn through the sides of the members, and means to lock the bar in the members.

4. A loose leaf binder comprising a frame having relatively adjustable members, a sleeve mounted in each member of the frame and having bar locking means formed therein, a telescoping sheet-mounting bar having each of its ends removably mounted in a sleeve, and having means formed in each end adapted to coöperate with the bar locking means of the sleeves to lock the ends of the bar therein.

5. In a loose leaf binder the combination of a frame having relatively adjustable members, a slotted sleeve mounted in each member of the frame, a telescoping sheet-mounting bar having each of its ends re-

movably mounted in a sleeve, and a pin mounted at each end of the bar adapted to engage the slot in the corresponding sleeve.

6. In combination in a loose leaf binder, a frame, a sleeve having a circuitous slot formed therein and mounted in the frame, a sheet-mounting bar removably mounted in the sleeve, and a pin mounted in the bar and adapted to coöperate with the circuitous slot to lock the bar in the frame.

7. A loose leaf binder comprising a frame having relatively adjustable members, a sleeve having a circuitous slot formed therein mounted in each member of the frame, a telescoping sheet-mounting bar having each of its ends removably mounted in a sleeve, and a pin mounted in each end of the bar and adapted to engage the circuitous slot in the corresponding sleeve.

20 8. In combination in a loose leaf binder, a frame having members transversely adjustable relatively to each other, and a transversely extending sheet-mounting bar removably mounted in and adapted to be withdrawn through the sides of the members.

25 9. In a loose leaf binder the combination of a frame having relatively adjustable side

members, a telescoping sheet-mounting bar having a plurality of parts removably mounted in and adapted to be withdrawn through a side member, and means to lock the bar in the members.

10. A loose leaf binder comprising a frame having adjustably connected members, a telescoping sheet-mounting bar having a plurality of parts removably mounted in and adapted to be withdrawn through a side of the connected members, and means to lock the bar in the members.

11. In combination in a loose leaf binder, a frame having adjustably connected side members, a telescoping sheet mounting bar having a plurality of parts removably mounted in the sides of the frame and adapted to be removed through a side of the frame from the outer face thereof, and means to lock the bar in the members.

In testimony whereof, I have hereunto subscribed my name this 23rd day of April, 1915.

CHARLES J. DUNBAR.
